UPGRADING CRACKED GASOLINE

Robert A. Findlay, Bartlesville, Okla., assignor to Phillips Petroleum Company, a corporation of Delaware

Filed Oct. 2, 1958, Ser. No. 764,993

3 Claims. (Cl. 208—70)

This invention relates to a method for upgrading cracked gasoline. In one aspect the invention involves the processing of heavy cracked gasoline in a series of mutually inter-related steps to obtain a plurality of high quality fuel stocks. In a more specific aspect the invention involves a step in which isobutane is dehydrogenated to isobutene, isobutane is alkylated with isobutene to form synthetic octanes, and heavy olefins are hydrogenated to form valuable saturated hydrocarbons, all three reactions being effected simultaneously in the presence of an HF alkylation catalyst.

With the trend of internal combustion engines requiring ever increasing octane number fuels for their operation, it is becoming increasingly apparent that future super-gasolines must consist largely of isoparaffins and aromatics because of the relatively high octane numbers of these components. The present process provides a method for more efficiently converting a heavy cracked gasoline to high octane streams and other fuel products of high quality.

It is an object of the invention to provide a process for converting heavy cracked gasoline in a more efficient and economical manner to high quality fuel products. Other objects, as well as aspects and advantages, of the invention will become apparent from a study of the accompanying disclosure and drawing.

According to the invention there is provided an integrated process comprising the steps of subjecting the gasoline to solvent extraction with a polar solvent to form a high octane aromatic gasoline extract stream and a raffinate stream; contacting the said raffinate stream with an HF catalyst and isobutane and thereby dehydrogenating a portion of said isobutane to form isobutene and alkylating isobutane with said isobutene while at the same time hydrogenating the olefins contained in the raffinate with hydrogen resulting from dehydrogenating of said isobutane, and recovering the products resulting from said contacting.

The invention will be better understood in connection with a description of the drawings, of which Figure 1 is a schematic flow diagram and Figure 2 is a flow diagram in more detail of zone 10 of Figure 1.

In the process of the invention the feed stock in line 1 is a heavy cracked gasoline which consists essentially of gasoline boiling in the range from 260° F. to the end point of the gasoline boiling range, usually about 400° F., and which results from the thermal or catalytic cracking of gas oils or reduced crudes. Small amounts of materials boiling below 260° F., say not more than 1 or 2 weight percent, can be present in the feed, but these are not desirable for reasons to be discussed hereafter. According to the present invention, this feed stock is subjected to solvent extraction in zone 2 with a polar selective solvent, such as diethylene glycol monomethyl ether containing 5-20 weight percent water, to produce an extract aromatic gasoline stream containing substantially all of the aromatics in the feed stream as extract and a raffinate stream containing most of the olefinic hydrocarbons in the feed stream. These olefinic hydrocarbons are mainly straight chain olefins and olefins of low branching produced by cracking, with some cyclic olefins. The cracked gasoline feed stock is fed through line 1 to extraction zone 2 countercurrent to the solvent entering

2

line 5. The extract phase is withdrawn through line 4 and passed to distillation zone 6 in which the extract hydrocarbons are separated from the solvent, which is recycled through line 17 to line 5. When the extraction solvent is the diethylene glycol monomethyl ether mentioned, the extraction is usually effected at a temperature in the range from 80-120° F., a solvent to feed weight ratio in the range from 10:1 to 20:1 and a reflux ratio in the range from 3 to 5. Conditions will, of course, depend upon the particular feed and solvent used.

Other examples of applicable solvents which can be mentioned are triethylene glycol, acetonitrile, diethylene glycol and sulfur dioxide.

The extract hydrocarbon passes from distillation zone 6 through line 7 and is an aromatic gasoline of high octane number. Since it will contain some diolefins it can be clay treated, if desired, for engine cleanliness. The raffinate stream passes through line 3 to deolefinizer-alkylator zone 10. The olefins in this stream contain 9 or more carbon atoms. It has been mentioned that the feed stream in line 1 can contain a small percentage of materials boiling lower than 260° F. However, this is undesirable since this can result in lower boiling olefins of 8 or fewer carbon atoms being present in zone 10. This is not desired because C₈ and lower olefins alkylate more rapidly than the desired heavier olefins, a reaction not desired in zone 10. An HF alkylation catalyst enters zone 10 through line 9, while isobutane is introduced to zone 10 through line 8. In this zone the C₉ and heavier olefins promote the dehydrogenation of part of the isobutane to isobutene, acting as hydrogen acceptors, and becoming saturated in the process. Isobutene is then alkylated with the resulting isobutene to produce a high quality alkylate, mainly 2,2,4-methylpentane containing a smaller amount of the other tri-methylpentanes. After the reaction in zone 10 excess isobutane is separated from the reaction products and is recycled from zone 10 to line 8 to be introduced to the reaction zone.

The reaction effluent from zone 10, minus the isobutane, passes from zone 10 through line 11 to zone 12 where it is fractionated into a plurality of cuts. From line 13 there is passed a cut containing a high proportion of synthetic octanes produced in the alkylation reaction and boiling up to about 250° F. Preferably, the end point of this cut is 240° F. in order to eliminate any small amount of methyl heptanes which can be present due to side reactions or due to a small amount of methyl heptanes in the original feed stock in line 1 should this feed stock not be sharply cut. The next cut is a saturated gasoline cut taken through line 14, with an end point of about 400° F. This cut contains the hydrogenated C₉+ paraffinic hydrocarbons produced in zone 10. It is an excellent feed to a catalytic reforming operation to produce further high octane gasoline since it is virtually sulfur-free and olefin-free and contains considerable amounts of naphthenes, employing methods and catalyst known to the art. The third cut passes from distillation zone 12 through line 15. This material is highly paraffinic since it forms in the main by the small extent of unavoidable alkylation of the heavier olefins, useful as such as a high grade jet fuel, boiling mainly over 400° F. Alternatively, this cut can be processed by thermal reforming to form high octane motor fuel.

The box 10 or deolefinizer-alkylator zone is shown in more detail in Figure 2. Zone 10 is the portion within the dotted lines, and lines 3, 8 and 11 are as previously described with respect to Figure 1. Raffinate in line 3 is charged to reactor 18, while fresh isobutane in line 8 is introduced to reactor 18 together with recycle isobutane and some HF in line 19, through line 20. Reactor effluent is withdrawn through line 21 to separator or phase

separation zone 22. The heavier acid phase is recycled to the reactor through line 23, while the lighter hydrocarbon phase containing a small portion of the HF catalyst passes to the deisobutanizer 24 through line 25.

The conditions employed in the reaction zone 18 are generally in the following ranges: temperatures 80-100° F., contact time 3-20 minutes, pressure to maintain liquid phase, liquid volume ratio of HF to hydrocarbons 0.1:1 to 2:1, mol ratio of isobutane charged to olefins charged 10:1 to 15:1. The HF alkylation catalyst ideally contains as little water as possible, but amounts up to 5 weight percent are operable, although it is preferred to operate using acid containing less than two weight percent water.

It will be seen that the processing scheme of the invention is highly advantageous when the ordinary operations necessary according to the prior art to upgrade a feed stream such as that of lines 3 and 8 are considered. Ordinarily, the isobutane would have to be dehydrogenated or cracked in order to produce isobutene for alkylation with isobutane. Then a separate step would be required to alkylate isobutane with isobutene. A further separate step would also be required to hydrogenate the olefinic hydrocarbons in line 3 to produce a saturated hydrocarbon cut suitable for feed to a reforming zone. This would be an expensive step because of the high cost of hydrogen and of operation at high pressures and temperatures for the hydrogenation. Thus, the three steps of the invention, dehydrogenation, alkylation and hydrogenation, are combined in a novel manner in deolefinizer-alkylator zone 10. By eliminating from zone 10 essentially all olefinic materials of fewer carbon atoms than 9, the alkylation in the zone is almost entirely between isobutane and isobutene, thus avoiding undesired alkylation between isobutane and lower olefins such as C_5 to C_8 olefins which alkylate much more rapidly than C_9+ olefins. There is thus avoided consumption of isobutane to form the less valuable and only moderately branched C_9 to C_{12} paraffins which would otherwise be formed if these lower olefins were present. On the other hand, the presence of the slowly alkylatable C_9+ olefins promotes the dehydrogenation of a portion of the isobutane, thus enabling the isobutene to be formed in situ, and thereby promoting the alkylation of isobutane with isobutene. At the same time the C_9+ olefins which are acting as hydrogen acceptors become saturated to form a valuable feed stream for catalytic reforming to produce more high octane gasoline.

Olefins in gasoline resulting from cracking of a hydrocarbon feed stock are quite stable under the conditions existing in the deolefinizer-alkylator zone and do not undergo appreciable scission to form lower olefins. On the other hand, polymer gasoline or gasoline containing substantial amounts of olefins resulting from the polymerization of lower olefins, would be undesirable as feed stocks to the present process. This is because liquid polymer olefins are relatively highly branched and would undergo scission to lower olefins, and alkylation of isobutane with these olefins would result in substantial amounts of C_5 , C_6 and C_7 isoparaffins appearing in the product from the deolefinizer-alkylator zone.

Elimination of most aromatics from the feed stock to the reaction step of the process has another beneficial result in reducing to a practically insignificant amount the formation of acid-soluble-oils in the reaction; that is, oils which are soluble in the HF acid phase and must be eventually eliminated from the catalyst phase, as is well known in the art of HF alkylation. Attempts to treat a cracked gasoline without the preliminary extraction step have resulted in conversion of as much as 15 percent of the olefins to acid-soluble-oils. The preextraction not only prevents this but also provides a high quality fuel, as previously discussed.

The following tables summarize a specific example of

the invention according to the process described with respect to Figures 1 and 2.

Feed (line 1): Heavy cut (260-400° F. boiling range) of catalytically cracked gasoline, 5 lbs./hr.

516

Solvent: Diethylene glycol monoethyl ether containing 11 weight percent water.

As will be evident to those skilled in the art, various modifications of this invention can be made or followed in the light of the foregoing disclosure and discussion without departing from the spirit and scope of the disclosure or from the scope of the claims.

I claim:

1. An integrated process for producing a plurality of high quality fuel products which comprises the steps of subjecting a gasoline resulting from cracking of a hydrocarbon stock and boiling in the range above about 260° F. to solvent extraction with a polar solvent to form a high octane aromatic gasoline extract containing substantially all of the aromatics in the feed and a raffinate containing most of the olefinic hydrocarbons in the feed; contacting the said raffinate with an HF catalyst and isobutane at a temperature in the range from 80 to 100° F., a contacting time from 3-20 minutes, and using a liquid volume ratio of HF to hydrocarbons in the range from 0.1:1 to 2:1 and a mole ratio of isobutane charged to olefins charged in the range from 10:1 to 15:1, and thereby in said contacting step dehydrogenating a portion of said isobutane to form isobutene and alkylating isobutane with said isobutene while at the same time hydrogenating the olefins contained in the raffinate with hydrogen resulting from dehydrogenating of said isobu- 20 25

tane in said contacting step, and recovering the products resulting from said contacting.

2. Process of claim 1 wherein the products are recovered and separated by removing unreacted isobutane and catalyst from the effluent from said contacting step and then separating the remaining effluent into a first gasoline boiling range cut boiling up to about 250° F., a second cut boiling in the range from about 250° F. to about 400° F., and a third cut higher boiling than said second cut.

3. Process of claim 1 wherein the products are recovered and separated by removing unreacted isobutane and catalyst from the effluent from said contacting step and then separating the remaining effluent into a first gasoline boiling range cut boiling up to about 240° F., a second cut boiling in the range from about 240° F. to about 400° F., and a third cut higher boiling than said second cut.
